WATCH OR SIMILAR ARTICLE

Lawrence W. Sparks, Bergen County, N. J., assignor to Vacheron & Constantin-Le Coultre Watches, Inc., New York, N. Y., a corporation of New York

Application August 29, 1956, Serial No. 42,767

Term of patent 14 years

(Cl. D42—8)

FIG. 1

FIG.4

Fig. 1 is a top plan view of a watch or similar article, showing my new design;

Fig. 2 is a bottom plan view thereof;

Fig. 3 is a side elevational view thereof; and

Fig. 4 is an enlarged view partly in side elevation and partly in section taken on broken line 4—4 of Fig. 1, from which it will be understood that the minute indicator is mounted on a disc positioned above the hour indicator, such disc being of transparent material so that the hour indicator will be visible.

I claim:

The ornamental design for a watch or similar article, substantially as shown.
